UNITED STATES PATENT OFFICE.

FREDERICK L. HEUGHES, OF ROCHESTER, NEW YORK.

SIDEWALK-LIGHT.

1,048,694.

Specification of Letters Patent. Patented Dec. 31, 1912.

Application filed June 17, 1912. Serial No. 704,257.

To all whom it may concern:

Be it known that I, FREDERICK L. HEUGHES, a citizen of the United States residing at Rochester, in the county of Monroe and State of New York, have invented 5 certain new and useful Improvements in Sidewalk-Lights, of which the following is a specification.

This invention relates to sidewalk lights 10 and has for its object to provide a construction comprising a knocked down iron framework and glass lenses therein isolated from each other, which construction is watertight and in which a broken lens can be 15 readily replaced without disturbing the other lenses. These and other objects of my invention will be fully illustrated in the drawings, described in the specification and pointed out in the claims at the end 20 thereof.

In the accompanying drawings, Figure 1 is a perspective view of the iron framework which constitutes a part of my invention. Fig. 2 is a section on the line 2^x-2^x of Fig. 25 1 with the glass lens in place.

In the accompanying drawings like reference numerals refer to like parts.

The frame is composed of a system of main bearing bars 1 which are made quite 30 deep and which have stiffening flanges 2, 2 on each side thereof at about the middle line thereof. These main supporting bars are recessed at suitable intervals as indicated at 3 to receive the cross bars 4, 4 which are 35 also suitably recessed as indicated at 5. These cross bars are provided with bottom flanges 6, 6 on each side thereof. The recesses in the main bars and the cross bars are cut to such a depth that when the parts 40 are assembled the flanges 6, 6 on the cross bars will come on a level with the flanges 2, 2 of the main bars 1. When a series of main bars and cross bars are assembled they will form between them a series of pockets 45 having four vertical walls around them and having flanges projecting inwardly therefrom, all of said flanges being on substantially the same level. The tops of the cross bars occur preferably slightly below the tops 50 of the main supporting bars, as is indicated in Fig. 2, so that the top of the main supporting bar can be battered down so as to securely lock the cross bars in place.

The flanges 6, 6 on the cross bars are cut 55 away as indicated at 7 for the purpose of receiving or providing an opening for the

flanges 2, 2 of the main bars. As shown in Fig. 1, the flanges 6, 6 are cut away at right angles to the cross bars. If desired the flanges 2, 2 may be cut away instead or the 60 flanges 2, 2 and 6, 6 may be cut away on a bevel of 45 degrees so as to form a mitered joint with each other, but either of these constructions is objectionable as they weaken the main supporting bars and for 65 this reason the cutting should be confined as much as possible to the cross bars. The main supporting bars 1 are cross or X-bars, so called, and the cross or transverse bars 4 are inverted T-bars, and when suitably recessed and interlocked or halved together, the main bars and the transverse bars form between them spaces of uniform size adapted to receive and support the glass lenses therein, through which lenses the light is transmitted through the sidewalk to the opening therebelow. These glass lenses are large 70 enough to almost fill the opening and leave space between the lens and the surrounding upright bars of the frame for a filler of 75 cement.

In Fig. 2 the lens is indicated at 8 and the cement at 9. A worm of putty 10 may also be interposed between the lens and the supporting flanges of the frame, although this 85 worm of putty is not really necessary except when an old lens must be replaced by a new one.

When the glass lenses are in place as is shown in Fig. 2 and the spaces between the 90 lenses and the bars are filled in with cement or other waterproof filling material, the sidewalk becomes absolutely waterproof and no water can penetrate therethrough. Furthermore, if any of the lenses become 95 broken they can be easily removed and replaced by new lenses without disturbing any of the other lenses that may be supported in the frame, and the new lenses will be as watertight as the old ones.

The glass lenses have the same vertical thickness at 11 on all four sides, and the margin is adapted to rest on the flanges of the bars by which the lens is supported and makes equal contact with all of the four 105 flanges 2 and 6 provided in the opening which it fills.

The structure is set up by placing the main bars 1 in parallel relation to each other and placing the cross bars 4 thereupon in 110 proper position, spacing the main bars 1 apart from each other at the proper dis-

tances. The tops of the recesses 3 in the main bars are then battered down as shown in Fig. 2, for the purpose of locking all the parts securely together. The lenses are then dropped in place either directly upon the supporting flanges 2 and 6 or upon the worm of putty interposed between the lenses and said flanges, and the spaces between the lenses and the upright flanges are filled in 10 with cement, as shown in Fig. 2, which cement is leveled off even with the top of the lenses.

This application describes another form 15 of my invention which is shown in my prior application No. 643,809.

Having thus described my invention, what I claim as new and patentable is as follows:

1. In a sidewalk light, the combination 20 of parallel main bars, each of said bars having a relatively wide vertical flange and a narrow transverse side-supporting and stiffening flange on the opposite sides thereof adjacent the neutral axis thereof, the main bars being solid from the bottom up to a line above and parallel to the transverse flanges, cross-bars interlocked or halved 25 with said main bars, said cross-bars having supporting flanges on each side thereof, 30 said main bars and said cross-bars forming pockets between them having said inwardly projecting flanges at the bottom thereof, glass lenses supported by said flanges and projecting above said bars, and a cement

filler filling in the space between said lenses 35 and said bars.

2. In a sidewalk light, the combination of parallel main bars, each of said bars having a relatively wide vertical flange and a narrow transverse side-supporting and stiffening flange on the opposite sides thereof adjacent the neutral axis thereof, the main bars being solid from the bottom up to a line above and parallel to the transverse flanges, cross-bars interlocked or halved 40 with and placed transverse to said main bars, said cross-bars having supporting flanges on each side thereof, the parts being joined together so that the supporting flanges on the cross-bars and main bars are 45 substantially on a level with each other, the flanges on the bars of the one set being cut away to receive the flanges on the bars of the other set transverse thereto, said main bars and said cross-bars forming pockets 50 between them having said inwardly projecting flanges at the bottom thereof, glass lenses supported by said flanges and projecting above said bars, and a cement filler filling in the spaces between said lenses and 55 said bars.

In testimony whereof I affix my signature in presence of two witnesses.

FREDERICK L. HEUGHES.
